UNITED STATES PATENT OFFICE.

JAMES W. McDONOUGH AND HORACE H. ELDRED, OF NEW YORK, N. Y.

TELEPHONE-SWITCH.

SPECIFICATION forming part of Letters Patent No. 357,682, dated February 15, 1887.

Application filed August 16, 1884. Serial No. 140,673. (No model.)

To all whom it may concern:

Be it known that we, JAMES W. McDONOUGH and HORACE H. ELDRED, citizens of the United States, and residents of New York, 5 in the county of New York and State of New York, have invented certain new and useful Improvements in Telephone-Switches, of which the following is a specification.

Our invention relates to apparatus for use at a station of a telephone-line, and is designed to furnish a means whereby the proper operation of the switching apparatus operated by the user of the telephone may be insured, and derangement of the apparatus or failure 15 to operate the switch, through inattention, ignorance, or neglect, may be avoided.

Our invention consists, primarily, in the combination, with the apparatus, of an electric alarm in a circuit so arranged that if the user 20 of the telephone shall hang it up without turning back the switch to normal position the circuit of the alarm will be automatically completed by the hanging up of the instrument, and the person at hand will be thus advised of 25 the neglect.

Our invention consists, further, in the combination, with a telephone-support, of a guard or check suitably arranged to prevent the telephone from being removed for use until the 30 switch is operated to complete the proper circuits, and an alarm whose circuit is partially completed by the switch when thus operated, and is wholly completed when the telephone is hung up, so that the alarm will sound 35 while the telephone is hung up, and the switch at the same time remains out of normal position, or position to lock the telephone, but will cease to sound if the switch be restored to normal position.

Our invention consists, further, in certain minor details and combinations which will be more specifically stated in the claims.

In carrying out our invention we may use any form of alarm, but prefer to employ an automatic vibrator-bell. The circuit for said bell may be any circuit containing a battery, or other source of electricity, but we generally prefer to make the circuit a local one. To avoid the employment of an extra battery, 50 we have arranged the circuits so that the battery for the telephone-transmitter may be utilized for the purposes of the invention.

Some of the forms and arrangements of apparatus or switching appliances that may be used in carrying out our invention are illustrated in the accompanying drawings, Figures 55 1 and 2, where we have shown the telephone apparatus of a station in perspective, with the proper electrical connections. We do not, however, wish to be understood as limiting ourselves to the particular devices shown, as the electrical circuits might be completed by other devices properly arranged to close the respective circuits when the switch is thrown in one or the other direction, and automatically by 65 the act of hanging up the telephone for the purposes herein described.

The invention is illustrated, partly in diagram, in Figs. 1 and 2 of the drawings.

A indicates in outline the case or box containing or supporting the various devices hereinafter described.

B indicates a magneto-generator and bell of the ordinary or suitable construction adapted to give an alarm or signal by currents sent 75 from a distant station, or to send currents for calling up a distant station.

D indicates a switch-lever pivoted on the casing A and connected with line L. Its end may be thrown into contact with either of two 80 studs, a b, the latter of which is connected with the magneto-bell B, and so to the continuation of the line L, or to earth, while the former, a, is connected with the same wire L, through the receiving-telephone C, wire 8, and secondary 85 of the induction-coil I. When the switch-lever D is in its normal position, or upon stud b, the telephone-receiver is cut out or rendered inoperative, while the apparatus B is in circuit and in condition to send or receive a bell-signal 90 in the ordinary way. By turning the lever to stud a the signal apparatus is thrown out and the telephone is thrown into circuit for use in oral communication. The throwing of the switch from its normal position to the position 95 just described completes the circuit for the primary of the induction-coil, the transmitter T, and the local battery L B, by means of a contact-spring, F, carried by the lever D, and a stud, c, in the path of the spring, in the obvious and well-known manner.

The transmitter is of any desired construction, that indicated being of substantially the construction shown in patent to J. W. Mc-

Donough, No. 246,800, and composed of a sound-receiving surface carrying electrodes through which the local circuit of L B is completed.

5 The parts, so far as described, are of the ordinary construction and adapted for use in the ordinary way. They are described and shown merely as a type of telephone apparatus for calling and communicating, and a description of the 10 manner of applying our present invention to them will be sufficient to enable any one skilled in the art to apply it to any other of the forms of apparatus and arrangements of circuits employed in the art.

15 In carrying out our invention we make suitable provision whereby in the normal position of the switch (of whatever form it may be) the telephone-receiver C shall be locked or held, so that it cannot be removed from its 20 support, and can only be removed or handled for use by operating the switch so as to make the proper change in the circuit to throw said telephone into operative electric circuits. One way of effecting such object is by making the 25 switch-lever or some attachment thereto act as an obstruction to prevent the removal of the telephone from its hook. This may be done in the manner indicated by placing a telephone hook or support, E, immediately 30 beneath the stud b, upon which the lever rests when the telephone is out of circuit and the bell in. The handle of the lever or other projecting part is then over the hook and the ring H upon the telephone cannot be slipped from the hook. By moving the lever to the stud a, 35 however, obstruction no longer exists to the taking down of the telephone for use.

It will be seen from the above that the user 40 naturally throws the telephone into circuit and the bell out of circuit in the action necessary to take down the telephone. In order that he may be made to restore the switch to its normal position after hanging up the telephone, we provide the electric alarm, which is 45 made to sound so long as the switch remains thrown against the stud a after the telephone is hung up.

R indicates the alarm, which may be of any 50 desired or suitable construction. We prefer to make it an automatic vibrator, which will ring so long as its circuit through a battery remains complete. Its circuit through battery L B is completed for this purpose automatically by the act of hanging up the telephone. 55 One way that may be employed for causing this to be done consists in making the hook E and the ring H close the circuit by coming into contact with one another. The ring H is connected by a flexible conductor, W, or otherwise, with one pole of the battery L B, through any suitable circuit-controller, such as will be presently described, that is operated with the switch when thrown away from normal position and against stud a, while the 65 hook E is electrically connected through the bell R with the other pole of the battery.

The circuit-controller, operated by the switch, consists, simply, of the spring G, carried upon the lever, but out of electrical connection therewith, and stud m, against which the spring G bears while the lever is against stud a. The springs F and G are in electrical connection, being formed from a common piece of metal. As will be obvious, when the lever has been turned to throw the telephone into circuit, the effect of hanging up the telephone without throwing the switch back to normal position is to cause a continuous ringing of the bell R, whose circuit from L B is then complete through E, H, W, m, G, F, and c. Not until the switch is thrown back to normal position, so that the local circuit will be broken at m G, will the bell cease to ring.

Any suitable circuit-closing devices may be used in place of the spring G and stud m, the 85 purpose being, so far as this element of the combination is concerned, to complete one break in the circuit of an alarm automatically by the act of throwing the switch to put the circuits for the oral communicating apparatus 90 into operative condition. So, also, other means might be employed for completing a circuit by the act of hanging up the telephone, or restoring said telephone to its normal position, the purpose being merely to automatically close a 95 break in the circuit of the alarm by the mere act of hanging up the telephone, or restoring it to normal position.

Instead of using a separate flexible cord, W, we may accomplish the same results by simply placing the hook or ring H in direct electrical connection with one of the binding-posts on the telephone-receiver C, preferably that one connected to the stud a, and electrically connecting the stud m with the stud a, as shown in Fig. 2. Such connection may be formed by a screw passing through the shank of the ring H, as indicated in Fig. 2, into the shank of the binding-post. In this diagram we have shown another form of the transmitter before referred to. It consists, as indicated, simply of the conducting-blocks a a, in which rest loosely the bars or rods b, all preferably of carbon, and supported in accordance with the patent before mentioned upon a suitable dia-phragm, T. The circuit by which the bell R is rung when the telephone is hung up is in this case completed as follows: From one pole of battery L B to bell R, hook E, ring H, binding-post of telephone C, wire connected thereto, stud a, stud m, springs G F, stud c, and to the other pole of the battery. The effect is obviously, as already described, to cause the bell to ring while the telephone is hung up and the switch is at the same time away from its normal position.

What we claim as our invention is—

1. The combination, with a telephone apparatus, of a switch for throwing the telephone into and out of action, and an alarm having two breaks in its circuits, one of which is closed by the switch when in position to place

the telephone in action, and the other by the telephone when hung upon its support.

2. The combination, with a telephone apparatus, of an alarm, and a local circuit therefor, completed by the telephone-receiver when the latter is hung upon its support without previous restoration of the telephone-switch to its normal position, as and for the purpose described.

10 3. The combination, in a telephone apparatus, of a local alarm-bell, a transmitter-battery, and extra connections from the latter to the alarm, a telephone-support, and a circuit-controller operated by the telephone-switch in the act of throwing the telephone apparatus into and out of operative condition.

20 4. The combination, with a telephone apparatus, of an electric vibrator alarm, a local circuit therefor, a switch for throwing the telephone apparatus into and out of operative condition, and circuit-controlling devices for said circuit, one operating with the switch and closed when the telephone apparatus is thrown into operation, and the other operated by the telephone and completing the circuit when the latter is hung up after use.

25 5. The combination, with a telephone support and switch, of a guard that normally, or while the telephone is out of action, prevents the telephone from being removed from its support, an alarm-bell, and a circuit therefor controlled jointly by the telephone switch and

the telephone, as described, so that the telephone can be removed from its support for use only by operating the switch, while the bell will ring if the telephone be hung up without restoring the switch to its normal position.

5 6. The combination, with a telephone-switch, of a telephone support, a guard arranged in the manner described to prevent the removal 40 of the telephone from its support when the switch is in its normal position, an alarm-bell and a circuit therefor having two breaks in series, one of which is closed in the act of throwing the switch from normal position, 45 while the other is completed in hanging up the telephone.

7. The combination, with a telephone apparatus, of a telephone-support guarded to prevent the removal of the telephone from its 50 support when the telephone-switch is in position to throw the telephone out of action, an alarm-bell, and a circuit therefor having connections to the telephone-support and the part of telephone resting on said support, as and 55 for the purpose described.

Signed at New York, in the county of New York and State of New York, this 6th day of July, A. D. 1884.

JAMES W. McDONOUGH.
HORACE H. ELDRED.
